WITNESS:

John Hanson
INVENTOR
BY *Victor J. Evans*
ATTORNEY

UNITED STATES PATENT OFFICE.

JOHN HANSON, OF DOYHOF, TERRITORY OF ALASKA.

TRAWLING SWIVEL.

Application filed July 23, 1921, Serial No. 487,097. Renewed December 27, 1922.

To all whom it may concern:

Be it known that I, JOHN HANSON, a citizen of the United States, residing at Doyhof, in the Territory of Alaska, have invented new and useful Improvements in 5 Trawling Swivels, of which the following is a specification.

This invention relates to apparatus used by fishermen, particularly to swivels, and has 10 for its object the provision of a swivel which may be used in a line for catching fish of any kind where the use of a swivel is necessary, the present invention contemplating the provision of a spring within the body of the 15 swivel whereby to permit a certain degree of resilience when a fish strikes so that the line may give and so that danger of losing the fish will be greatly reduced.

An important object is the provision of 20 a device of this character which is so constructed that the swivel or eye pins may be removed when worn and which is likewise so constructed that the spring within the interior of the body may be replaced in case 25 of breakage or in the event of its becoming weak and worn.

Another object is the provision of a device of this character which will be simple and inexpensive in construction, which will 30 resist the action of salt water on account of its materials, which will be highly efficient in use, durable in service, and a general improvement in the art.

With the above and other objects and advantages in view, the invention consists in 35 the details of construction to be hereinafter more fully described and claimed and illustrated in the accompanying drawings in which—

40 Figure 1 is a side elevation of the device, and

Figure 2 is a longitudinal sectional view therethrough.

Referring more particularly to the drawings, I have shown my swivel as comprising 45 an elongated body 10 having one end open and internally threaded, as shown, and having its other end closed except for a relatively small hole 11. This body 10 is formed 50 with a longitudinally extending bore 12 which extends entirely to the open end but which terminates short of the closed end, as shown. Associated with the closed end of this body is a swivel member formed as 55 a length 13 of suitable wire inserted through the hole 11 and having one end formed with

a retaining head 14. Externally of the body this wire member 13 is bent to form an eye or loop 15 and has its terminal portion wrapped about itself, as indicated at 16. 60

Threaded into the open end of the body is a plug member 17 which has its exterior contour substantially the same as the closed end of the body and which is provided with a longitudinal hole 18 through which is inserted a swivel member which has one portion 19 extending substantially throughout the length of the bore 12 and which is formed beyond the end of the plug 17 with an eye or loop 20, the terminal being coiled 70 as shown at 21. Disposed within the bore 12 is a coil spring 22 which has one end abutting against the plug 17 and which has its other end abutting against a disk or washer 23 movable within the bore. The 75 portion 19 of the second mentioned swivel member passes through this disk 23 and has its end formed with a head 24.

In the use of the device constructed and assembled as above described, it will be apparent that the swivel members will operate in exactly the same manner as other well known swivel members in so far as preventing tangling and raveling of the line is concerned. However, a distinct advantage of 80 the present device is that the spring 22 provides resilience so that when my device is interposed in a line and a fish strikes or bites upon a hook, breaking of the line or tearing of the fish's mouth with consequent escape, is prevented owing to the fact that the eye or loop 20 may move with respect to the body as one portion 19 of the former is connected with the spring-pressed disk. 85 In this way it will be seen that it is possible to make a larger catch of fish as danger of loss is reduced to the minimum. Another feature of advantage is that in the event of any possible corrosion or wearing away of the eyes or loops 15 and 20, the 90 swivel members may be quickly and easily removed and replaced by new ones so that the device should have an extremely long life and be comparatively free from destruction through wear. 95

While I have shown and described the preferred embodiment of my invention, it is of course to be understood that I reserve the right to make such changes in the form, construction and arrangement of parts 100 as will not depart from the spirit of the invention or the scope of the subjoined claim. 110

Having thus described my invention, I claim:

A device of the character described comprising an elongated body formed of separable sections having a screw threaded connection, one section being provided with a small bore and the other section being provided with a relatively large bore extending throughout the major portion of its length and being further provided with a somewhat smaller recess at the end of said bore, said other member being also formed with a longitudinally extending hole communicating with said recess, a member rotatably mounted within said longitudinally extending hole and provided at its free end with a head located within the recess and

having its other end formed with a swivel eye, a coil spring located within said bore, a washer longitudinally movably mounted within said bore and normally abutting against the shoulder defined by the junction of said bore with said recess, said washer having a central hole, a swivel member extending through the relatively small bore in said first named member and also extending through said spring and through the hole in said washer and being formed with a head and washer disposed within said recess and having its outer end formed with an eye.

In testimony whereof I affix my signature.

JOHN HANSON.
